UNITED STATES PATENT OFFICE.

OEDS T. KNIPER, OF OLEAN, NEW YORK.

DESIGN FOR A PICTURE-FRAME.

SPECIFICATION forming part of Design No. 32,732, dated May 29, 1900.

Application filed May 2, 1900. Serial No. 16,278. Term of patent 14 years.

To all whom it may concern:

Be it known that I, OEDS T. KNIPER a citizen of the United States, residing at Olean, in the county of Cattaraugus and State of New York, have invented a new and original Design for Picture-Frames, of which the following is a specification.

This invention relates to a new and original design for a picture-frame; and the essential feature resides in the formation of distinctly-projecting rectangular corners composed of triangular pieces applied to the outer edges of elongated space-strips having outer angular ends which are arranged at a right angle to the outer edges of the sides and ends of the frame.

The drawing illustrates a perspective view of a picture-frame embodying the features of the design, and therein the numeral 1 designates the sides, with outer opposite beveled ends 2, to which frame ends 3 have connected relation, and also constructed with outer opposite beveled end portions 4. The front faces of the sides and ends of the frame present a

molding appearance, and fastened to the beveled end portions 2 and 4 are diagonally-arranged space-strips 5, having their outer ends projected beyond and at a right angle to the outer edges of the sides 1 and ends 3 of the frame. The strips 5 are squarely united at the center, and thereon are placed mitered triangular corner-pieces 6, which, with the space-strips 5, produce rectangular projecting corners, in which the surface-molding configuration meets at the center in approximately the same contour as the said corners.

Having thus described the invention, what is claimed as new is—

The design for a picture-frame, herein shown and described.

In testimony that I claim the foregoing as my own I have hereto affixed my signature in the presence of two witnesses.

OEDS T. KNIPER.
